United States Patent Office

Des. 201,200
Patented May 25, 1965

201,200

WINDOW LATCH

Philip Crain, Valley Stream, N.Y., assignor to Allen-Stevens Corp., Woodside, N.Y., a corporation of New York

Filed June 20, 1963, Ser. No. 75,456

Term of patent 14 years

(Cl. D50—5)

Fig. 1.

Fig. 2.

Fig. 3.

FIG. 1 is a perspective view of a window latch showing my new design;

FIG. 2 is a view in elevation taken from the right of FIG. 1; and

FIG. 3 is a view in elevation taken from below FIG. 1. The dominant feature of my design resides in the portion shown in solid lines.

I claim:

The ornamental design for a window latch, as shown and described.
